UNITED STATES PATENT OFFICE.

HENRY J. KASCH, OF DAYTON, OHIO.

DESIGN FOR A KNOB OR THE LIKE.

Application filed December 7, 1926. Serial No. 19,962. Term of patent 7 years.

To all whom it may concern:

Be it known that I, HENRY J. KASCH, a citizen of the United States, and resident of Dayton, county of Montgomery, State of Ohio, have invented a new, original, and ornamental Design for a Knob or the Like, of which the following is a specification, reference being had to the accompanying drawing, forming a part hereof.

Fig. 1 is a top plan view and Fig. 2 is a side elevation of a knob showing my new design.

I claim:

The ornamental design for a knob or the like, substantially as shown.

In testimony whereof, I have hereunto set my hand this 23rd day of November, 1926.

HENRY J. KASCH.
